[57] CLAIM

The ornamental design for a front panel of a protective vest, as shown and described.

DESCRIPTION

FIG. 1 is a perspective view as seen from the front and left of a front panel of a protective vest showing my new design on a user;

FIG. 2 is a front elevational view thereof in a flattened condition not on the user;

FIG. 3 is a front elevational view thereof as shown in FIG. 2 with the broken line illustrated attachment portions removed;

FIG. 4 is a top plan view thereof;

FIG. 5 is a cross-sectional view thereof taken along line 5—5 of FIG. 3 to show the layers of the protective vest that provide the unique appearance;

FIG. 6 is an enlarged cross-sectional view thereof of the area 6—6 shown in FIG. 5; and,

FIG. 7 is an enlarged perspective view of the area 7—7 shown in FIG. 3.

The broken line illustration in the drawing disclosure is for illustrative purposes and forms no part of the claimed design.

The fragmentary criss-cross pattern shown in the drawing is understood to represent fabric and is repeated uniformly throughout the areas shown.
